J. S. DUMAS

ELECTRIC HEATER

Filed August 25, 1923

Joseph S. Dumas,
Inventor

William L. McLean
Attorney

UNITED STATES PATENT OFFICE.

JOSEPH S. DUMAS, OF MONTREAL, QUEBEC, CANADA, ASSIGNOR TO WILLIAM T. DONNELLY, OF MONTREAL, CANADA.

ELECTRIC HEATER.

Application filed August 25, 1923. Serial No. 659,295.

My invention relates particularly to electric heaters of the portable type adapted to the dual purpose of heating and cooking and it has for its object to eliminate certain defects of devices of this nature heretofore known and at the same time reduce the cost of manufacture and facilitate assembling.

To this end my invention consists of the particular construction, arrangement and combination of parts hereinafter set forth and pointed out in the claims.

For full comprehension, however, of my invention, reference must be had to the accompanying drawings in which similar reference characters indicate the same parts, and wherein:

Figure 1 is a perspective view of my electric heater;

Figure 2 is a similar view showing the heater arranged as a cooking stove;

Figure 3 is a side elevation with some of the parts broken away to more clearly illustrate the internal construction;

Figure 4 is a section view taken on line 25 4—4 Figure 3;

Figures 5, 6 and 7 are detail views; and

Figure 8 is a sectional view taken on line x—x Figure 6.

The preferred embodiment of my invention consists of two parts hinged together to serve either as a standing closed heat radiator, an oblique open foot warmer or a flat topped double element cook stove. Each part consists of a pair of decorated filigree plates 2 forming two sides of a chamber, the side which serves as the top of the stove being presented by a plate 3 uniting the side plates by flanges 4 fastened to the side plates by screw bolts and nuts 5 and forming one side of a sub-chamber 6, the other sides of which are presented by flanged segments 7 and a disc or plate 8 preferably asbestos. This sub-chamber contains the refractor 9 in which the heating element 10 is carried.

The connection of the refractor in place is by a pair of screw bolts and nuts 12, the bolts being passed through the refractor and through one of the flanges 13 of the angular segments and through the asbestos disc 8, the nut clamping these parts together and the surface of the asbestos being protected by washers 14. The asbestos disc is cut away as at 15 to expose a pair of binding posts 16 mounted in the refractor and having the opposite ends 17 and 18 of the ele-

ment connected thereto while one of these binding posts is connected by a lead 19 to one of the switches 20, the other switch, 21, being similarly connected to one end of the element of the other part of the heater. The other binding post is connected by a lead 25 to the element in the other part of the heater by means of a similar binding post similarly mounted in the other refractor. A porcelain terminal block 27 is mounted on the inside of the filigree side plate near the last mentioned binding post and has an integral bushing 28 projecting through the side plate. The main lead cable 30 from the source of electrical supply enters through this bushing, one lead being connected to the adjacent binding post 16 and the other to a binding post 31 on the terminal block which is connected to one of the terminals of the switch 20 by a lead 33. This terminal is connected to the corresponding terminal of the switch 21 by a lead 35, these leads 25 and 35 which are common to the two parts of the heater, therefore, of necessity, pass out of one of these parts into the other in order to enable these leads to have freedom of movement to assume different positions to accommodate the change of position of the parts of the heater in their hinged relation. The sub-chamber containing the refractor and the various leads just described as well as the porcelain terminal block are enclosed and protected by an angular housing plate fitted in place and formed to present a flat middle portion 40 and oblique end portions 41 and 42, when fitted in place the end portion 41 engages within a lip 43 on the top plate 5 while the opposite end engages against the plate 5 in the vicinity of the inner end of a lip 44 on the plate 5 near the hinged end of the heater parts, the middle portion of the plate resting on supporting lugs 45 to which the plate is connected by screws 46. The oblique end 42 of this plate has a pair of openings 47 in which porcelain bushings 50 are set, their outer ends having heads 48 and their inner ends spring wire fastenings 51 screwed thereon and effectively locking the bushings in the plate. The leads 25 and 35 pass through these bushings and the relatively large bore of the latter permit them to move freely over the wires when it is necessary or desirable to open the heater by removing screws 46 and detaching and swinging back plate 40 thus exposing practically

all the devices which make up either part of the heater to facilitate repairs or inspection. The curved ends of the filigree plates at the bottom of the heater form legs 60 while the curved ends at the top afford means for connecting a pair of handles 61; and the switches 20 and 21 have porcelain bases 70 and porcelain buttons 71, the latter being relatively large to serve as feet for the 10 heater when used as a foot warmer.

Operation.

When in use as a heater the parts are closed together and stand on the legs 60. 15 When used as a foot warmer the parts are swung two-thirds open or to an obtuse angle and then rest on these legs 60 and the feet presented by the buttons 20 and 21. When opened out flat the heater presents a two-element stove.

To inspect the internal connections the screws 46 are removed and the plate 40 swung down to position thus exposing the internal parts.

25 What I claim is as follows:—

1. A combination electric heater and stove consisting of two parts hinged together each part comprising a pair of side plates, a combined side and top plate secured to and connecting together the said side plates, the last mentioned plate having a middle opening, a pair of flanged segments upon the underside of the last-mentioned plate and coinciding with the opening therein; a heat 30 insulating disc or plate covering the space enclosed by the segments thus forming a chamber; a refractor containing a heating element and carried within the chamber; means securing the refractor in place; means 35 housing the sub-chamber; and means for connecting the elements of the respective refractors to a source of electric supply.

2. A combination electric heater and stove consisting of two parts hinged together each 45 part comprising a pair of side plates, a combined side and top plate secured to and connecting together the said side plates, the last mentioned plate having a middle opening, a pair of flanged segments upon the underside 50 of the last mentioned plate and coinciding with the opening therein; a heat insulating disc or plate covering the space enclosed by the segments thus forming a chamber; a refractor containing a heating element carried 55 within the chamber; means securing the refractor in place; said means consisting of clamping means uniting together the flanged segments, refractor and plate or disc of heat insulating material; means housing the sub- 60 chamber and means for connecting the elements of the respective refractor to a source of electric supply.

3. A combination electric heater and stove 65 consisting of two parts hinged together each part comprising a pair of side plates, a com-

bined side and top plate secured to and connecting together the said side plates, the last mentioned plate having a middle opening, a pair of separate flanged segments secured to the underside of the last mentioned 70 plate and coinciding with the opening therein; a heat insulating disc or plate covering the space enclosed by the segments thus forming a chamber; a refractor containing a heating element carried within the chamber; means securing the refractor in place; said means consisting of clamping means uniting together the flanged segments, refractor and plate or disc of heat insulating material; means housing the sub-chamber 80 and means for connecting the elements of the respective refractors to a source of electric supply.

4. A combination electric stove and heater 85 consisting of two parts hinged together each part comprising a pair of side plates, a combined side and top plate secured to and connecting together the said side plates, the last mentioned plate having a middle opening; a pair of flanged segments secured to 90 the underside of the last mentioned plate and coinciding with the opening therein; a heat insulating disc or plate covering the space enclosed by the segments thus forming a chamber; a refractor containing a heating element carried within the chamber, the refractor carrying a pair of binding posts and the insulating disc being cut away to expose the same; electrical connections between the heating element and the binding posts; means securing the refractor in place; means housing the sub-chamber and means for connecting the elements of the respective refractors to a source of electric supply.

5. A combination electric heater and stove 100 consisting of two parts hinged together each part comprising a pair of side plates, a combined side and top plate secured to and connecting together the said side plates, the last mentioned plate having a middle opening, a 105 pair of flanged segments secured to the underside of the last mentioned plate and coinciding with the opening therein; a heat insulating disc or plate covering the space enclosed by the segments thus forming a chamber; a refractor containing a heating element and carried within the chamber; means securing the refractor in place; means housing the sub-chamber consisting of an angular plate presenting a flat middle portion 110 and oblique end portions; means securing said housing plate in position enclosing the sub-chamber and its electrical connection, one of the oblique ends of said plate having 115 a pair of openings containing bushings of electrical insulating material accommodating certain of the electric leads extending from one heating element to other of the heater parts.

6. A combination electric heater and stove 125

consisting of two parts hinged together each part comprising a pair of side plates, a combined side and top plate secured to and connecting together the said side plate, the last mentioned plate having a middle opening, a pair of flanged segments secured to the underside of the last mentioned plate and coinciding with the opening therein; a heat insulating disc or plate covering the space enclosed by the segments thus forming a chamber; a refractor containing a heating element and carried within the chamber; means securing the refractor in place; means housing the sub-chamber; a porcelain terminal block secured to one of the side plates 15 of one part of the heater and having an internal bushing projecting through the said side plate, a pair of main leads from a source of electrical supply entering through the bushing of the terminal block and electrical connections between these leads and the heating elements.
